ESCAPEMENT MECHANISM

George E. Nicholson and John B. McGay, Tulsa,
Oklahoma, assignors to Precision Products, Inc.,
Tulsa, Oklahoma, a corporation of Oklahoma

Application October 16, 1944, Serial No. 558,894

1 Claim. (Cl. 58—122)

1

This invention relates to timer movements and more particularly, but not by way of limitation, to an escapement mechanism wherein power is transmitted directly from the escapement wheel to the balance wheel to cause oscillation thereof.

An important object of this invention is to provide an escapement mechanism of the above nature adapted for use in a timer movement wherein it is necessary that a fixed period of rotation be maintained although various amounts of power will be required to be taken from the timer mechanism during the fixed period of rotation.

Another object of this invention is to provide an escapement mechanism for accurately governing a timer movement which is transmitting an excessively high power which can be utilized for other purposes and still not cause over-banking of the balance wheel in the escapement mechanism.

And still another object of this invention is to provide an escapement mechanism of the above nature wherein there is a simple self-starting arrangement that eliminates all friction or drag against the balance staff of the mechanism.

A further object of this invention is to provide an escapement mechanism which is simple in construction, inexpensive in manufacture, efficient and durable in use.

With these and other objects in view there has been illustrated on the accompanying drawing, one form in which the invention may be conveniently embodied in practice.

Fig. 1 is an enlarged plan in showing the escapement mechanism in dead beat position.

Fig. 2 is a similar view showing the mechanism in impulse position.

Fig. 3 is a similar view to Fig. 1 showing with the impulse completed.

Fig. 4 is also a similar view showing the mechanism at the end of its reset position.

Fig. 5 is an enlarged fragmentary sectional elevational view of the escapement mechanism.

Referring to the drawing in detail wherein like reference characters denote corresponding parts throughout the various views, the numeral 10 indicates a balance wheel rigidly mounted on a shaft 12 floatingly disposed in bearings 14 and 16 secured in spaced clock plates 18 and 20. As disclosed in Fig. 5, a stud 22 is secured in plate 18 and is provided with a hair spring 24 connected to the balance wheel shaft 12. It is to be noted that the shaft 12 has a cutaway portion 26 for cooperating with the escapement lever

which will hereinafter be referred to. An escapement lever 28 is pivoted on a shaft 30 fixed between the plates 18 and 20. An escapement wheel 32 is fixed to a main shaft 34 in turn fixed between the plates 18 and 20. The escapement wheel is provided with a plurality of peripheral teeth 36, each of which is constructed so as to provide straight flat face 38 and an angular face 40.

10 The escapement lever 28 is provided with a substantially circular central portion 42 having extending legs 44 and 46. The leg 44 has an apertured anchor 48 provided with extending legs 50 and 52. The leg 50 has a projection or pallet 54 acting as the discharging end and is provided with an angled or inclined front face 56 which will hereinafter be described. Similarly leg 52 has a projection or pallet 58 acting as the receiving end, however, no angled face is provided 15 as in 54. A counterweight 60 is disposed adjacent anchor 48. The end of leg 46 is provided with a pair of prongs 62 and 64 having a recess or slot 66 adapted to cooperate with a roller pin 68 provided on a strut 70 of the balance wheel 10.

20 In operation, the escapement shaft 34 and wheel 32 are adapted to receive power from a main spring of a clock works (not shown). From Fig. 1 it is to be noted that the hair spring 24 has oscillated the balance wheel to a dead beat 25 position wherein the roller pin 68 is in alignment with the center of the anchor 48 and the balance staff pin 12. With power applied to the escapement wheel 32, a tooth thereof is brought into contact with the angular face 56 of the pallet 54, thereby causing oscillation of the anchor 48 to provide a swinging movement of the lever 28 in a counterclockwise direction according to Fig. 1. Counterclockwise movement of the lever causes the prong 62 to contact the roller 30 pin 68 and provide a clockwise rotation of the balance wheel 10. The cutaway portion 26 allows for movement at the prongs 62 and 64 through the shaft 12. The angular face 56 of the pallet 35 54 provides for a simple self-starting arrangement of the mechanism as will be hereinafter explained. With the anchor 48 and lever 28 moving counterclockwise, the receiving pallet 58 provided is placed in a position to contact a tooth 36 of the escapement wheel 32, however, on the 40 return of the balance wheel 10 by the counterforce of the hair spring 24, the escapement lever is moved to the right or clockwise according to Fig. 2, thereby removing the receiving pallet 58 out of contact with the teeth 36 to bring the 45 escapement mechanism to an impulse position as

50

shown in Fig. 2. In this position a tooth 36 of wheel 32 is brought into direct contact with the roller pin 68 on the balance wheel 10 to cause a counterclockwise rotation (as shown in Fig. 2) of the balance wheel against the action of the hair spring 24.

Alluding to the self-starting feature, practically all prior self-starting escapement mechanisms are so constructed that there is a drag, or friction, against the balance staff, especially where the application of power is directed through an escapement lever to the balance wheel. This is caused where the teeth of the escapement wheel are provided with a power or lift angle and bearing against the lever directs this power through the escapement lever against the balance staff. The present structure precludes this possibility because there is a positive lock provided between the escapement teeth 36 and the discharging and receiving pallets. The teeth 36 and the pallets 54 and 58 are not provided with a power or lift angle. The inclined or angled end portion 56 of the pallet 54 mainly facilitates a self-starting arrangement of the mechanism from a dead beat position as shown in Fig. 1, instantaneous as power is applied to the escapement wheel. In any position other than dead beat (Fig. 1), the escapement wheel is either moving so as to bear against pin 68, or is positively locked by either the receiving or discharging pallets. The angled face 56 has a very slight impulse effect in a clockwise direction on the balance wheel.

With the impulse completed as shown in Fig. 3, it is to be noted that the roller pin 68 has been moved out of the recess 66 and away from a tooth 36 of the wheel 32, thereby placing the discharging pallet in a locked position with a tooth 36 of the wheel 32. At the completion of the impulse, the counterforce of the hair spring rotates the balance wheel 10 in a clockwise direction according to Fig. 4 to move pin 68 into the slot 66 and cause movement of the escapement lever in a counterclockwise direction according to Fig. 4, and bring the discharging face 54 out of contact with a tooth 36 and placing the receiving face 58 into contact with a tooth 36. The operation continues as long as power is applied to the escapement wheel.

In the present invention the application of power from the escapement wheel directly to the roller pin of the balance wheel to cause rotation thereof, has the advantage over conventional escapement mechanisms of substantially lessening friction on two normally longer lifting faces of the pallets thereof, thereby providing a more efficient operation by the utilization of less torque. In the present mechanism, the speed of oscillation of the balance wheel, compared to the power and mass of the escapement wheel, tends to limit effectual operation of the balance wheel. Power being applied to the escapement wheel of a certain mass, it follows that it has a certain moment of inertia, and with the balance wheel oscillating at a definite rate of angular velocity as it passes its neutral or dead-beat position, then an equilibrium between the escapement wheel and the balance wheel is reached whenever the power to the escapement wheel is not sufficient to raise the attained angular velocity of the escapement wheel up to or beyond the attained angular velocity of the balance wheel as the balance wheel passes its neutral position. When this point of equilibri-

um is reached, there ceases any flow of power from the escapement wheel to balance wheel through pin 68 until the rate of angular velocity of the balance wheel has decreased. In the present structure, the escapement wheel in moving through its impulse, transmits power to the roller pin 68 only when the angular velocity of the roller pin on the balance wheel is less than the attained angular velocity of the escapement wheel. By this arrangement, a wide range of power can be applied to an escapement wheel of a certain mass without causing the balance wheel to oscillate beyond its limits or "overbanking," thereby, preventing a timing mechanism from keeping correct time. Furthermore, the additional power provided in the escapement wheel can be utilized for other purposes such as a resetting mechanism in a clock meter and still not cause overbanking of the balance wheel when such additional power is not being used.

From the foregoing, it will be apparent that the present invention permits the use of escapement mechanism to govern the accurate running of heavy duty clocks, and furthermore can be readily utilized in for economical timing devices which are prone to cease running when becoming slightly dirty due to the close ratio of spring power to the escapement wheel. The present high power escapement mechanism would keep this type of time mechanism running irrespective of a small amount of debris and the like. Furthermore, the temperature changes in cheaper time mechanisms affect the lubrication oil and sometimes cause them to stop, and use of the present high power escapement mechanism would preclude this detriment.

Changes may be made in the specification and drawings without departing from the spirit of the invention within the scope of the following claim as set forth.

We claim:

In an escapement mechanism having a power driven toothed escapement wheel, a balance wheel having a roller pin directly engaged by the teeth of the escapement wheel, an escapement lever having a pair of pallets, one of said pallets having an inclined face, a tooth of the escapement wheel disposed in contact with the approximate center of the inclined face at the instant the balance wheel oscillates past the neutral position in a clockwise direction, a forked portion on the escapement lever contacting the roller pin, said forked portion and a tooth of the escape wheel both acting on the roller pin at the same distance from the axis of the balance wheel.

GEORGE E. NICHOLSON.
